Filed Feb. 12, 1968, Ser. No. 10,546

Term of patent 3½ years

Int. Cl. D22—09

U.S. Cl. D22—19

FIG. 1

FIG. 2

FIG. 3

FIG. 1 is a front elevational view of a lantern-type insect trap showing my design;

FIG. 2 is a top plan view thereof; and
FIG. 3 is a bottom plan view thereof.

It is to be understood that the lattice-like ornamental pattern is repeated throughout the upper and lower surfaces of the drawing figures.

The dominant features of my design reside in the portions shown in full lines.

I claim:

The ornamental design for a lantern-type insect trap, as shown and described.
